D 18,509

UNITED STATES PATENT OFFICE.

CHARLES H. DURPHY, OF CHICAGO, ILLINOIS.

DESIGN FOR AN ADVERTISING-CARD.

SPECIFICATION forming part of Design No. 18,509, dated August 7, 1888.

Application filed February 2, 1888. Serial No. 262,830. Term of patent 14 years.

To all whom it may concern:

Be it known that I, CHARLES H. DURPHY, a citizen of the United States, residing in Chicago, in the county of Cook and State of Illinois, have invented and produced a new and original Design for Advertising-Cards, of which the following is a specification.

Reference is had to the accompanying photograph, forming a part of this specification, which shows a face view of the design.

The leading feature of my design consists in a central horseshoe-like figure composed itself of smaller figures to present the appearance of a horseshoe made of horsenail-like figures arranged radially with their points toward the center and their heads outside. This may be formed in any manner and of any material, and is the prominent object upon the card. At each side of the horseshoe-like figure are oblique rows of horse-nail-like figures, and beneath are horizontal rows of the same. The

distinctive peculiarity, however, of the design is not the shape of the board upon which the surface ornamentation is displayed, nor the arrangement of the rows of nail-like figures in oblique and horizontal lines; but that which strikes the eye is the horseshoe-like figure composed of horse-nail-like figures occupying a central position upon the card in the midst of horsenail-like figures otherwise arranged. 25 30

I claim—

The design for an advertising-card wherein the prominent central object is made up of smaller horse-nail-like figures arranged radially with their points toward the center and their heads outside, the other matter of the advertising-card being arranged around the central figure, as shown and described. 35

CHARLES H. DURPHY.
